UNITED STATES PATENT OFFICE.

CHARLES H. PERKINS, OF LACONIA, NEW HAMPSHIRE, ASSIGNOR TO CRANE MANUFACTURING COMPANY, OF LAKEPORT, NEW HAMPSHIRE, A CORPORATION OF NEW HAMPSHIRE.

KNITTING-MACHINE.

1,211,872.

Specification of Letters Patent. Patented Jan. 9, 1917.

Application filed May 8, 1916. Serial No. 96,081.

To all whom it may concern:

Be it known that I, CHARLES H. PERKINS, of Lakeport, in the city of Laconia, county of Belknap, and State of New Hampshire, have invented certain new and useful Improvements in Knitting-Machines, of which the following is a specification.

The present invention consists in certain improvements upon the knitting machine set forth in United States Letters Patent of John S. Crane, No. 1,027,034, May 21, 1912.

The improvements relate, first, to a new organization of knitting cams in an independent circular dial knitting machine so that the loops drawn down by the cylinder needles shall land on the spring beards of the dial needles; second, to a new presser which yieldingly presses upon the spring beards of the dial needles to insure their taking and casting off the old loops; and, third, in a yarn guard located between the yarn feed and the presser.

The improvements are illustrated in the accompanying drawings, in which—

Figure 1, is a plan view of so much of a circular dial knitting machine having independent spring needles as is necessary for an understanding of the present invention. Fig. 2, is a vertical section in the plane indicated by the line 2—2 in Fig. 1. Fig. 3, is a front view of a portion of the machine illustrating the yarn guard in position. Fig. 4, is a detail front view of the yarn guard detached. Fig. 5, is a detail front view of the presser. Fig. 6, is a detail plan view showing the relative action of the cylinder and dial needles. Fig. 7, is a vertical section indicated by the line 7—7 in Fig. 6. Fig. 8, is a section in the plane indicated by the line 8—8 in Fig. 6.

The improvements are illustrated in the drawings as embodied in a machine of the type wherein the needles and their carriers rotate, while their actuating devices and the feeds are mounted on fixed supports. The machine may be of the type wherein a plurality of yarn feeds and of knitting cams are employed; but, as the yarn feeds and knitting cams are all just alike only a single

yarn feed and the coöperating knitting instrumentalities are illustrated.

There are two sets of spring beard needles, *a*, *a*, being the main needles and *b*, *b*, being the ribbing needles. The main needles *a*, *a*, as shown, are carried upon a rotating cylinder *A*, upon the periphery of which they are guided and attached in such manner as to permit them to reciprocate vertically under the action of cams which are similar to those disclosed in the aforesaid Patent No. 1,027,034, one only of which (the draw cam) is indicated at *c*, in Fig. 2, of the present drawings. The ribbing needles *b*, *b*, are carried by a rotating dial *B*, and are adapted to reciprocate radially on said dial by cams which are mounted upon and beneath a normally stationary cam or cap plate *C*, which is superposed above the dial *B*. The knitting cams for the ribbing needles act in usual manner (as in said Patent No. 1,027,034) except for the action of the throw out cam *D*. This cam *D*, is so shaped and located with respect to the yarn feed and to the draw cam *c*, for the main needles that the loops drawn down by the main needles land upon the tops of the beards of the dial needles as said dial needles are being moved outwardly by the action of said cam *D*, as illustrated in Figs. 6 and 7, of the drawings.

The yarn feed may be of any well known character but is illustrated as similar to that shown in United States Letters Patent of John S. Crane, No. 880,013, February 25, 1908. As shown in Figs. 1 and 2, of the present drawings there is a rotary feed wheel *E*, carrying radially movable sinkers *d*, which are thrust radially outward by proper cams in a well known way so as to enter between the elevated main needles *a*, thereby sinking the yarn loops between the shanks of the main needles beneath their beards. The yarn, indicated at *e*, in Fig. 1, is delivered to the sinkers through a yarn guide *F*. The yarn having been thus delivered to the main needles *a*, said needles are drawn down by the action of the draw cam *c*, so as to engage the yarn presented to the

said needles by the sinkers. The main needles *a*, descend below the shanks of the ribbing needles as illustrated in Figs. 3 and 7. During the action of the sinkers and 5 the downward movement of the main needles *a*, the ribbing needles *b*, are being thrust outwardly by the throw out cam *D*, as illustrated in Fig. 6. The ribbing needles are still moving outwardly when the main 10 needles are drawn below the ribbing needles. Fig. 7, shows the relative position of one of the main needles and one ribbing needle when the main needle has just passed completely below the ribbing needle. This position is that indicated by the section line 7—7 15 in Fig. 6 of the drawings. As shown by Figs. 6 and 7, when a main needle has thus been drawn down below the neighboring ribbing needles on both sides, the ribbing 20 needles are still moving outwardly and the points of their beards have not reached the plane of the main needles. The consequence is that the new loops drawn down by the main needles are landed on top of the beards 25 of the ribbing needles instead of being landed on the shanks of the ribbing needles as in the case of the machine of the aforesaid Patent No. 1,027,034, as well illustrated in Figs. 33 and 34, thereof. This landing of 30 the loops on to the spring beards of the ribbing needles relieves the yarn of strain thereby preventing the breakage of the yarn and the casting off of stitches, and it also aids in the drawing of the stitch. This action 35 is due to the relative location of the two draw cams *D* and *c*. Cam *D*, is located to the rear of cam *c*, so that its projecting action is continuing after that of the cam *c*, has resulted in bringing the main needles 40 below the shanks of the ribbing needles. After the yarn has been landed on top of the beards, the ribbing needles continue their outward movement under the action of the throw out cam *D*, until the beard of the 45 needle has passed entirely through the new loop *f*, as illustrated in Fig. 8, and in Fig. 6, at the section line 8—8. The new loop *f*, rides off the beard and is drawn down on to the shank of the ribbing needle as illustrated in Fig. 8. The dial or ribbing needles *b*, are supported at their outer ends by the usual horizontal supporting plate *G*, while receiving the loops and until they have been retracted beyond the reach of the presser as 50 shown in Fig. 1. After the new loops have been laid upon the shanks of the ribbing needles, said needles are drawn inwardly by the draw cam illustrated in dotted lines at *H*, in Fig. 1. During this drawing in movement the beards of the ribbing needles encounter the presser *I*, which depresses the point of each beard after it has passed over the new loop and before the old loop *g*, is reached (Figs. 7 and 8) so that, during the

completion of the drawing in movement of 65 each ribbing needle, the old loop rides over the beard and is cast off. This is a well known action being disclosed, for example, in said Patent No. 1,027,034.

The cams *D* and *H*, are such that the 70 ribbing needles are given but a single outward movement, that is to say, after these needles have commenced to retract under the influence of the draw cam *H*, there is no subsequent outward movement until after 75 the old loops have been cast off and the next knitting operation is to be performed. In other words, the ribbing needles have a single outward travel and a single inward travel during each knitting operation. The 80 new loops are landed on top of the spring beards of the ribbing needles, as shown in Fig. 7, while the ribbing needles are moving outwardly and before said needles reach their extreme outward position. That is 85 to say, after a new loop *f*, as shown in Fig. 7, has landed upon the spring beard of a ribbing needle *b*, that needle continues its outward movement to the position shown in Fig. 8, during which final outward move- 90 ment the new loop *f*, rides off of the spring beard and by the further action of the draw cam *c*, is landed on top of the shank of the ribbing needle and clear of the old loop *g*, on that needle. It is a frequent happening, 95 in knitting with the usual arrangement of spring needles and cams, especially with linty yarns, or where a knot occurs, or where the old stitches are loose, that a new loop is laid on a needle shank so close to the 100 old loop as to be engaged thereby or entangled therewith, with the result that the beard point of the ribbing needle on its retraction passes beneath the new loop as well as the old loop thereby dropping a 105 stitch with a resulting defect in the fabric. In accordance with the present invention, the new loop being landed upon the spring beard while still moving outwardly, is subject to the frictional engagement of the 110 spring beard so that the new loop is kept clear of the old loop; and, when the new loop escapes from the point of the beard, it lands upon the needle shank at an always 115 clear distance from the old loop, as shown in Fig. 8, so that on the retraction of the ribbing needle, the point of the beard is sure to pass over the new loop before it is depressed and enters beneath the old loop.

The presser *I*, consists of a plate secured 120 at the front end of a rock shaft *J* (see Fig. 1) which is journaled in a bracket *K*, carried by the fixed cap plate *C*. A coiled spring *L*, fastened at opposite ends to the shaft *J*, and the bracket *K*, acts to yield- 125 ingly press the lower free end of the presser *I*, against the beards of the ribbing needles as the latter pass beneath the presser, as

illustrated in Fig. 5. The spring L, is more forcible than the beards which co-act at any one time with the presser so that the beards are closed by the presser until after the old loops ride on to the top of the beards. The presser has a handle h, by means of which it can be lifted free from the ribbing needles when desired. The lower edge of the lower free end of the presser is shaped so as to bear upon the desired number of ribbing needles.

Between the feed wheel E, and the presser I, is located the yarn guard M. This guard has a vertical shank i, which is guided in a bracket N, fixed to the cap plate C. This shank i, extends above the bracket N, as shown in Fig. 3. A contractile spring O, is fastened at its upper end to the upper end of the shank i, and at its lower end to the bracket N, so that the yarn guard M, is yieldingly pressed downwardly. This yarn guard M, is above the ribbing needles, and its lower edge rests yieldingly upon the beards of the ribbing needles as said needles are moving outwardly and approaching their complete outward movement and hence during the period that the new loops are held upon the tops of the beards of the ribbing needles. This guard keeps the yarn in position on the beards. This yarn guard is located above the main needles when drawn down, and in substantially the same plane as the shanks of said needles. The lower bearing edge of the guard extends along the path of the main needles (Fig. 1) and it is above a plurality of said needles, as shown in Fig. 3. It is so located that the main needles are drawn beneath the ribbing needles before they reach it, as shown in Fig. 3. The yarn guard M, assists in evening the loops in forming the stitch. The spring O, has just tension enough so that if one or two beards of needles under the foot of the guard stand higher than the rest the guard levels them down to the correct plane, and consequently the yarn forming the loops is distributed so as to make the loops of the same length, thereby producing an even looking fabric.

I claim—

1. An independent needle circular knitting machine having a main set of spring beard needles and a set of ribbing spring beard needles, in combination with a yarn feed supplying yarn to the main needles, a draw cam for the main needles, and a draw cam for the ribbing needles, the relative location of said draw cams being such that the main needles are drawn down beneath the ribbing needles while the ribbing needles are moving outwardly and before the beards of the ribbing needles pass outwardly beyond the main needles so that the yarn drawn downwardly by the main needles lands upon the spring beards of the ribbing needles.

2. An independent needle circular knitting machine having a main set of spring beard needles and a set of ribbing spring beard needles, in combination with a yarn feed supplying yarn to the main needles, a draw cam for the main needles, a throw out cam and a draw cam for the ribbing needles, said cams for the ribbing needles acting to give but one throw out travel and one draw in travel at each knitting operation and the said draw cams for the main and ribbing needles being relatively located so that the main needles are drawn down beneath the ribbing needles while the ribbing needles are moving outwardly and before the beards of the ribbing needles pass outwardly beyond the main needles so that the yarn drawn downwardly by the main needles first lands upon the spring beards of the ribbing needles and subsequently upon the shanks of the ribbing needles as the said ribbing needles complete their outward movement.

3. An independent needle circular knitting machine having a main set of spring beard needles, a set of ribbing spring beard needles, and a fixed cap plate within the circle of main needles, in combination with a bearing fixed to said cap plate, a presser acting upon the spring beards of the ribbing needles as they are drawn inwardly to cast off the old loops, such presser consisting of a plate the lower edge of which acts upon the beards of the ribbing needles and a horizontal rock shaft turning in said bearing, and a spring acting upon the rock shaft and causing the presser to yieldingly bear upon the beards of the ribbing needles.

4. An independent needle circular knitting machine having a main set of spring beard needles and a set of ribbing spring beard needles, a yarn feed which feeds yarn to the main needles, a throw out cam for the ribbing needles, and a presser bearing upon the beards of the ribbing needles as they are drawn in to cast off the old loops, in combination with a yarn guard located between the said yarn feed and said presser, and a spring acting upon the yarn guard causing it to press yieldingly upon the beards of the outwardly moving ribbing needles, the bearing edge of said presser being located in substantially the same plane as the shanks of the main needles.

5. An independent needle circular knitting machine having a main set of spring beard needles and a set of ribbing spring beard needles, a yarn feed which feeds yarn to the main needles, a throw out cam for the ribbing needles, a presser bearing upon the beards of the ribbing needles as they are drawn in to cast off the old loops, in combination with a yarn guard located between the said yarn feed and said presser, and a spring acting upon the yarn guard causing

it to press yieldingly upon the beards of the outwardly moving ribbing needles.

6. An independent needle circular knitting machine having a main set of spring beard needles and a set of ribbing spring beard needles, a yarn feed which feeds yarn to the main needles, a throw out cam for the ribbing needles, a presser bearing upon the beards of the ribbing needles as they are

drawn in to cast off the old loops, in combination with a yarn guard located between the said yarn feed and said presser with its lower edge just above the outwardly moving ribbing needles. 10

In witness whereof, I have hereunto signed my name. 15

CHARLES H. PERKINS.
